(57) **CLAIM**

The ornamental design for a dock piling ring as shown and described.

DESCRIPTION

FIG. 1 is a perspective view of the dock piling ring of the present invention;

FIG. 2 is a front view thereof;

FIG. 3 is a back view thereof;

FIG. 4 is a top view thereof;

FIG. 5 is a bottom view thereof; and,

FIG. 6 is another perspective view thereof, shown with additional broken line environment.

The portions of the dock piling ring illustrated in broken lines form no part of the claimed design.
